INVENTOR.
BY *William S. Mirtle*

ATTORNEY.

UNITED STATES PATENT OFFICE.

HYLAND L. CUSICK, OF PITTSBURGH, PENNSYLVANIA.

RULE HOLDER.

1,403,942.

Specification of Letters Patent. Patented Jan. 17, 1922.

Application filed May 1, 1920. Serial No. 378,295.

To all whom it may concern:

Be it known that I, HYLAND L. CUSICK, a citizen of the United States of America, residing at Pittsburgh, in the county of Allegheny and State of Pennsylvania, have invented certain new and useful Improvements in Rule Holders, of which the following is a specification.

The present invention relates to rule holders, and has several advantageous features which are new and useful. My invention is devised so that it can be firmly attached to an ordinary "two-foot" rule, and be inserted in the hip-pocket of a mechanic without raising his eyes from the work in which he may be engaged at the time. Another advantageous feature is the fact that my device holds the rule securely in the one corner of the pocket, and prevents the rule from getting cross-wise in the pocket, while still another feature of my invention is the means used to yieldingly hold the rule in the pocket, all of which will be more fully described hereinafter in this specification.

In the accompanying drawings forming part of this specification I have illustrated one complete example, and a modification of my invention, constructed according to the best mode I have so far devised for the practical application of the principles of my invention.

Figure 1 is an elevational view of a rule held in position in a pocket, by means of my invention.

Figure 2 is a transverse section on line 2-2 of Figure 1.

Figure 3 is a side view of the invention in large detail.

Figure 4 is a side view of Figure 3, taken from the right of same.

Figure 5 is a top or plan view of Figure 3.

Figure 6 is a side elevational view of a modification of my invention illustrating an ornamental feature of same.

The numeral 1 indicates a rule, and 2 the bent metal clasp forming my invention. The latter is provided with a head 3 having two opposed flanges 4, 5 formed preferably integral with the portion 6, and having corrugations 7, 7 adapted to grip the sides of the rule 1 as shown in Figure 1. It is also seen that the metal of the head 3 should be of sufficient thickness and of some "springing" tension between the flanges 4 and 5, so that when once the clip 2 is adjusted in proper position on the rule, it will be next

to impossible to remove it therefrom, the height selected on the rule depending as seen from Figure 1 on the particular depth of the pocket 8 under consideration, as is readily understood. The head 2 is also provided with proper markings 10 to correspond with the gradations on the rule, so that no indicated space is lost when using the rule, and thus avoiding the necessity of sliding the clasp 2 along the edge of the rule, as would otherwise be necessary. The metal holder 2 has a downwardly extending resilient arm 11, formed preferably integral with the portion 6, and having a bent or curved portion 12, to provide a space 13 into which the material of the pocket 8 lodges between arm 11 and the edge 14 of the rule. The arm 11 has near its lower extremity, a returned end 15, which is spring-like in its nature, and as shown clearly in the drawings this returned portion 15 passes through an aperture 16 formed in the arm 11 and has also a lip-shaped terminal 17 of shape shown in Figures 3, 4 and 5. The purpose of the terminal 17 and spring end 15 is to enable the arm 11 to yieldingly grip the material of the pocket 8 as illustrated in Figure 1, and at the same time permit the removal of the rule as soon as the lip 17 is pressed outward and downward by the thumb of the user. One of the principal features of the invention in hand is that by means of my device with a little preliminary practice and familiarity with the device, a mechanic can without turning his head to look around engage the end 15 over the edge 18 of the pocket 8 when placing the rule 1 in the latter, the spring 19 at once gripping the pocket material between its face 20 and the face of the rule 14; and it is further seen that as the rule is placed in the corner of the pocket as illustrated in Figure 2, the edge of the pocket at 18 is curved around the sharp corner 21 of the rule 1, and while in this position the clasp or clip 2 prevents the rule from getting away from the corner of the pocket, and getting cross-wise in the pocket as is illustrated by the dotted lines 22. This latter feature is common when many of the clips at present in use are used, that is to say that such clips in that they do not secure the rule to the corner of the pocket, thereby permit the rule to become cross-wise in the pocket, and this is one of the disadvantages my type of clip seeks to overcome. From which it is seen that my

clasp or clip not only secures the rule in the pocket when the user bends over or stoops down for any purpose, which is the usual purpose of clips of the kind under consideration, but that my clip holds the rule upright in the pocket, and on account of the clip being on the edge 14 of the rule, rather than on the face 23, the user simply places the end 24 in the pocket, makes a movement 10 to the right until edge 14 is arrested by the corner 18 of the pocket 8, and then makes a downward movement until the bottom of the pocket is reached, the spring 15, engaging readily over the edge 18 of the pocket 15 without any attention. In removing the rule from the pocket if there is any tendency for the rule to "stick" or adhere to the cloth of the pocket, as sometimes happens with goods of thick material, it is evident 20 that a slight pressure outward, and downward on the lip 17 at once releases the rule, and permits its removal from the pocket. In connection with what has been said with reference to the rule getting cross-wise in 25 the pocket when no clip is used such as the present invention, it is seen that when the pocket 8 is of sufficient depth as to be say three-quarters the length of the rule, in this case the upper end 25 of the rule often gets 30 wedged under the thickened edge 26 of the pocket and when so wedged in the rule 1, is extremely hard to dislodge, and the more so if the pocket happens to be a "hip-pocket." This last described situation cannot occur 35 when my invention is attached to the rule, as is quite readily appreciated.

The modification shown in Figure 6 of

the drawings illustrates the point that these clips can be ornamented if desired in various ways, such as that shown, in which the 40 opposed flanges 4, 5 are perforated, or decorated by enamel designs or the like, which add to the attractiveness of the clip.

I claim:

1. A rule holder provided with a head, and 45 a downwardly extending arm with a slot formed therein, a returned resilient end on said arm having a reduced width portion adapted to reciprocate within the arm slot, and a lip-shaped terminal on the said returned end for disengaging the reduced width portion of the resilient end from a garment-pocket.

2. A rule holder having means for attachment to the edge face of a rule, and a downwardly extending arm provided with a slot, 55 an "S-shaped" returned and resilient end on said arm, a reduced width portion on the returned end reciprocally operating within the arm slot, and a widened and lip-shaped terminal on the said returned end for actuating the reduced width portion of the latter.

3. A rule holder having a downwardly extending arm with a slot therein, an "S-shaped" returned and resilient end on said 65 arm adapted to reciprocate within the arm slot, and a widened lip-shaped terminal on the returned end for disengaging the latter from a garment-pocket.

In testimony whereof I affix my signature. 70
HYLAND L. CUSICK.
